TRAVELING BORDER DISCHARGE TUBE
DISPLAY

Fred Hotchner, Los Angeles, Calif.

Continuation of application Serial No. 156,056,
December 20, 1926. This application August 7,
1929, Serial No. 384,170

8 Claims. (Cl. 177—346)

This invention relates to a traveling border discharge tube display and the object thereof is to produce a novel and attractive effect for an electric display in which discharge tubes are used as the illuminating elements in a traveling border. Heretofore similar effects have been produced by the connection of a number of short lengths of tubing together in a design of the type of a border and by suitable connections to a flasher the effect of shadows traveling through the design is produced by the illumination in a given order of the tubes. This method is extremely expensive because of the great number of units and uneconomical in operation because of the excessive energy loss when the tubing is used in short lengths due to the fact that amount of energy consumed without the production of useful radiation at the electrode is so great that tubes short enough to use for the purpose stated have very low efficiency. All traveling border effects of the prior art known to myself produce a traveling effect by the shifting of dark spots in effect through the border continuously in one direction. The borders are thus not continuous to the eye but consist of a series of light sections broken by the dark spots. It is one of the objects of this invention to provide a traveling effect in a border which is continuous and has no dark spots to break it up. It has also been proposed to use several tubes together in a design and arrange them in parallel relationship, pointing out the major portion of each tube leaving exposed consecutive sections of the several tubes. This method while reducing the number of the electrodes is also very inefficient because of the large proportion of energy consumed without the utilization of the radiation generated thereby.

The present invention provides a border in which the tubes may be made in as great a length as construction expedites permit. The entire energized column is utilized with the exception of the very small portions in the ends of the tubes where they turn into the body of the sign. The border may be made with an appreciable width thus increasing its attraction value and numerous designs may be used in the layout of the tubing within the scope of the invention. The present invention provides a border which produces a traveling effect without showing breaks to the eye in the border itself. At all instants of time the border appears continuous. The effect is very smooth, attractive and convincing.

An embodiment of the invention is shown in the accompanying drawing, although it is to be un-

derstood that the invention is not limited to the particular form shown but only by the prior art and the limitations imposed by the appended claims.

Figure 1 is a view of a portion of an electric sign having a traveling border made according to this invention.

Figure 2 is a perspective view of a portion of the border with the portion of the body upon which it is mounted shown broken away from the remainder of the sign to illustrate the relation of the various elements to each other and the method of supporting the tubes from the sign body.

Figure 3 is a wiring diagram illustrating one satisfactory method of flashing the tubes.

Figures 4, 5 and 6 are diagrams illustrating the sequence of the flashing of the tubes as effected by the device shown diagrammatically in Figure 3 and calculated to assist in a visualization of the effect produced.

In the drawing a border is illustrated on a typical electric sign. The sign is indicated by the numeral 1; the display face by 2; the letters by 3; and the border by 4.

The border is composed of the sinuous or undulatory discharge tubes 5, 6, 7; 5', 6', 7', etc. The length of the tubes is determined by the expedites of manufacture, the border consisting, so far as the effect is concerned, of three tubes extending the length thereof. If desired for practical reasons the tubes may be made in sections as short as desired and connected together electrically into groups following the general arrangements of the single tubes of the drawing. This might be done for instance, for the purpose of avoiding or reducing the cross over arrangement here shown. The tubes are provided with electrode terminals in the usual manner extending into bushings in the body of the sign and supported from the body of the sign by insulating posts as shown in Figure 2. The posts for supporting the tube furthest from the body are indicated by 8, the posts supporting the intermediate tube by 9, and the post supporting the tube closest to the body by 10. While the tubes are here shown as being supported in separate planes for the sake of clearness in illustration, they would ordinarily in practice be so made as to lie substantially in a single plane with the exception of the cross over sections which would be offset towards the body of the sign.

In Figure 3 a satisfactory method of flashing the display is illustrated. Each of the tubes, 11, 12 and 13 is individually connected to the secondary of one of the step up transformers 14, 15 and 16.

16. As applied to the sign shown in Figure 1, each of the tubes in the diagram would represent one series of tubes such as the entire group 5, 5¹, 5², 5³, etc., which would be flashed together, usually connected in series. The primary coils of the transformers are connected together with one terminal of each coil common and connected to one supply wire 17, and the other terminals connected to the three terminals 18, 19, 20 of the contactor 10 21 in such manner that upon the rotation of the rotor 22 the transformers are activated in rotation. The rotor is connected to the other supply wire 23.

The diagrams in Figures 4, 5 and 6, illustrate 15 the sequence of illumination of the tubes as effected by the contactor shown diagrammatically in Figure 3. An exact visualization of the optical effect cannot be realized from a line drawing due to the fact that the effect is very much of the 20 nature of an illusion. Not merely the light radiating directly from tubes is received by the eye, contributing to the illusion but also the reflected radiation from the body of the sign. While the 25 effect here described is referred to in this specification as a "traveling border" it is to be understood that this term is only used because no other is available in the vocabulary of the industry.

Instead of forming the border with three lines of tubing as shown in the illustration, four or more 30 lines of tubing may be used if desired with advantageous results. The particular design shown is merely illustrative as many other designs having the same general relationship of tubes may be used.

35 It is particularly to be noted that the entire length of the tube is effective, with the exception, of course, of the short sections at the ends which are turned back into the sign to make terminals. As each tube is lighted it presents to 40 the eye a continuous undulatory line of light along the border without breaks or dark spots. Likewise when the border is composed of a number of shorter tubes, as in Figure 1, the lighting of each series of tubes presents to view a continuous undulatory line throughout the entire border. Thus when the tubes (or the series) are 45 flashed, one at a time in sequence, the effect produced is that of the undulatory line shifting lengthwise through the border. Thus if we flash the tubes in a continuous sequence (1, 2, 3, 1, 2, 50 3, 1, etc.) the border appears to shift bodily continuously in one direction.

This effect is distinctly different from the prior art traveling borders, all of which to the best of 55 my knowledge are characterized by the effect of shadows running through a border rather than that of the border itself shifting.

This same flowing effect is produced by lighting 60 two tubes at a time, leaving one tube off, and flashing by lighting a tube in advance while dropping out a tube behind, thus: First instant, 1 and 2 are lighted and 3 dark; second instant, 2 and 3 are lighted and 1 dark; third instant 3 and 1 are lighted and 2 dark; and the operation repeated. Any number of tubes over three may be 65 used in the border, and in such cases any number less than the whole number of tubes may be lighted in each instant of the operation with the remainder dark. Thus, in a border of four tubes, one tube may be on with three tubes off, two may be on with two off, or three may be on with one off.

70 It is to be noted that it is also possible to make fractional divisions of the proportion of tubes on and off during the operation. Thus in the

case of a three tube border the contacts may be so made that they overlap in their operation, being longer than necessary to flash one tube at a time and shorter than necessary to flash two tubes on at a time. As a consequence, we will have this 80 condition: At one instant just one tube will be lighted, then the next tube will come on with the first mentioned tube held on for an instant when it goes off leaving the second tube on which burns alone for an instant and then the third tube comes on before the second tube goes off, and so forth. The result will be that, considered the 85 cycle of operations through, one and a fraction tubes were lighted with one and a fraction tubes dark. 90

This application is a continuation of the application filed by myself on December 20, 1926, Serial No. 156,056, entitled Discharge tube signs, which was inadvertently abandoned without abandoning the invention described and claimed 95 thereon.

Having thus described my invention what I claim is:

1. As a means for producing by luminous devices a visual effect indicative of progressive motion the combination with at least three elongated luminous elements arranged in staggered and overlapping relationship in the line of motion and means for causing the illumination of said elements in a given order. 100

2. An electric display consisting of a plurality of luminous tubes arranged in undulating lines to form a design, there being more than two of said lines and the tubes in said lines being of similar formation whereby the lines are substantially repetitions of each other, the forms in the tubes of each line being offset lengthwise of the lines from the corresponding forms in the other lines and means for flashing the tubes to illuminate the lines in a given order. 105

3. An electric display consisting of a plurality of luminous tubes arranged in undulating lines to form a design, there being more than two of said lines and the tubes in said lines being of similar formation whereby the lines are substantially repetitions of each other, the forms in the tubes of each line being offset lengthwise of the lines from the corresponding forms in the other lines and means for flashing the tubes to illuminate the lines in a given order the lines in which 110 120 125 the tubes are arranged being criss crossed.

4. An electric display for producing a visual effect indicative of progressive motion along a certain path comprising in combination a plurality of elongated luminous elements said elements having portions of similar form located in similar positions transversely of said path but spaced endwise along said path with respect to adjacent elements and means for illuminating and darkening said elements in a given order 130 135 along said path, said means maintaining more elements illuminated than dark.

5. A plurality of luminous tubes assembled to form an elongated design in which more than two similar sinuous lines are represented thereby extending generally in the direction of the longest dimension of said design, overlapping each other, and the formations of the same being displaced from each other in the direction of said design, whereby the energization of the tubes in said 140 145 lines one line after the other presents to view a sinuous line which appears to shift continuously in one direction, and means for flashing said tubes one at a time in such order.

6. A border display comprising a plurality of 150

5 luminous tubes assembled to form an elongated design in which more than two similar sinuous lines are represented by said tubes, extending in the direction of said border, overlapping each other to the view, and the formations thereof being displaced from each other in the direction of said border whereby the energization of said tubes one after the other creates the visual impression of the movement of a sinuous line of 10 light from one position to another in one direction through said border, said positions corresponding to said lines, and means to flash said tubes one at a time in such order.

15 7. An electric display consisting of a plurality of luminous tubes arranged in undulating lines to form a design, there being more than two of said lines and the tubes in said lines being of similar formation whereby the lines are substantially repetitions of each other, the forms in the 20 tubes in each line being offset lengthwise of the lines from the corresponding forms in the other

lines, and means to illuminate said tubes in such order that a pair of said lines present an illuminated design and appear to shift through said border in one direction continuously from position to position, said positions corresponding in 80 distance to the displacement between the lines.

8. An electric display consisting of a plurality of luminous tubes arranged in undulating lines to form a design, there being more than two of said lines criss crossing each other and the tubes in said lines being of similar formation whereby the lines are substantially repetitions of each other, the form in the tubes in each line being offset lengthwise of the lines from the corresponding forms in the other lines, and flashing means to illuminate said tubes in a continuously repeated sequence in which two adjacent lines are 90 illuminated at a time and appear to shift continuously in one direction through said border.
